US0D1070583S

(12) United States Design Patent (10) Patent No.: US D1,070,583 S
(45) Date of Patent:  Apr. 15, 2025

(54) BOX FOR COSMETIC PRODUCTS

(71) Applicant: GUERLAIN, Paris (FR)

(72) Inventor: Gabrielle Saint-Genis Rodriguez,
Paris (FR)

(73) Assignee: GUERLAIN, Paris (FR)

() Term: 15 Years

(21) Appl. No.: 35/520,211

(22) Filed: Feb. 21, 2024

(80) Hague Agreement Data

Int. Filing Date: Feb. 21, 2024

Int. Reg. No.: DM/235373

Int. Reg. Date: Feb. 21, 2024

Int. Reg. Pub. Date: Mar. 8, 2024

(30) Foreign Application Priority Data

Oct. 9, 2023 (EM) 015036611-0001
